ARROW REST FOR ARCHERY BOW
Clifford W. Cee, Otter Lake, Mich.
Filed June 26, 1961, Ser. No. 119,642
5 Claims. (Cl. 124—24)

This invention relates to improvements in arrow rest for archery bow. The principal objects of this invention are:

First, to provide an arrow rest which is adjustable in the window of an archery bow transversely of the line of flight of the arrow.

Second, to provide an arrow rest that is easily attachable to the side of the window of an archery bow at selectively varied vertical positions and which may be adjusted transversely according to the desires of the archer.

Third, to provide an adjustable arrow rest that yields with the released arrow and does not abnormally wear the feathers of the arrow.

Other objects and advantages of the invention will be apparent from a consideration of the following description and claims. The drawings of which there is one sheet illustrate a highly practical form of the arrow rest and one modified form of the rest.

FIG. 1 is a side elevational view with the arrow rest of the invention mounted thereon.

FIG. 2 is an enlarged fragmentary rear elevational view of the bow and arrow rest.

FIG. 3 is a still further enlarged fragmentary rear elevational view of the arrow rest attachment and its connection to the bow.

FIG. 4 is a top plane view of the arrow rest and its attaching and adjusting components.

FIG. 5 is a vertical cross sectional view taken along the plane of the line 5—5 in FIG. 4.

FIG. 6 is a top plan view of a first modified form of the arrow rest.

FIG. 7 is a rear elevational view of the modified rest shown in FIG. 6.

In the sport of archery it is now common to provide bows such as the bow indicated at 1 having an upper arm 2 and a lower arm 3 projecting oppositely from a central grip 4. The upper arm 2 is laterally offset from the grip 4 to provide a sight arrow window with a side wall 5 and ledge or floor 6. The bow string 7 when stretched between the ends of the arms lies in a plane passing vertically through the space defined by the window. The bow illustrated and described is known as a right hand bow, and reversely arranged left hand bows are common, but the arrow rest of the invention is adaptable to either right or left hand bows.

In accurate shooting by experienced bowmen, it is found that the side 5 and floor 6 of the window opening are not always at the right position for all bowmen or for a single Bowman under all conditions of shooting. The position of the shaft of the arrow as it is held in the window at the instant of release is an important factor in the accuracy of the bow and the present invention provides an arrow rest which is adjustable to accommodate the desires of different shooting conditions and different bowmen.

The arrow rest consists of a generally rectangular box-like housing 8 having forwardly and rearwardly projecting attaching ears 9 on its inner edge which receive screws 10 for selectively attaching the box to the side surface 5 of the window. The box may rest generally on the floor 6 of the window or may be raised to selected higher positions. Moulded plastic has been found to be a suitable material for the box but other materials could obviously be substituted. The box is open at the top having an overhanging rim 11 as a retainer and is open at its inner

2

side as at 12 to permit the insertion of a slide block 13 prior to assembly of the box on the bow. The block 13 is transversely drilled and tapped as at 14 to receive and engage the threaded end of an adjusting screw 15 passed through the outer end wall 16 of the box. A spring 17 may be positioned around the screw between the block and the inside of the box to hold the block in adjusted position on the screw 15.

The block 13 is further vertically drilled as at 18 to receive an upstanding post 19 which projects substantially above the box 8. The post 19 defines an annular groove 20 within the drill hole 18 which is engaged by a keeper screw 21 to retain the post in the drill hole while permitting rotation of the post. A convolutedly coiled spring 22 positioned around the post has one end 23 anchored in the block and the other end 24 anchored in the post 19 to bias the post to a yieldably adjusted position of rotation. A laterally projecting arm 25 projects outwardly from the window opening and forwardly of the bow in the at rest position of the post 19.

As appears most clearly from FIGS. 2 and 3, the upper end of the post 19 and the arm 25 form a right angled supporting corner for the arrow indicated by the dotted lines at 26. It is further apparent that the post 19 and the arm carried thereby can be adjusted transversely of the bow to a variety of positions, one of which is illustrated by the dotted lines at 19A. When the shaft of an arrow is supported on the arm 25, the upper and outer feathers are completely out of contact with the rest of any other part of the bow. The lower inner feather 27 is disposed partially across the intersection of the arm 25 and post 19 and is forced rapidly thereacross as the arrow is released. However, the forward motion of the arrow and feather cause the arm 25 and post 19 to rotate forwardly against the compression of the spring 22 thus yielding slightly with movement of the feather 27 and minimizing wear of the feather on the arrow rest.

The modified form of arrow rest attachment shown in FIGS. 6 and 7 provides the same variability in vertically adjusted installation and in transverse adjustment after mounting on the body, but provides a somewhat different detail of arrow engaging support. To this end the box 8, screw 15 and spring 17 may be the same as in the first form of the invention. The block 13B threadedly engages the screw 15 and fixedly or non-rotatively supports a modified post 19B. The post 19B supports a laterally projecting pin 25B which may be a separate metal pin as indicated or may be an integral projection on the upright pin. The laterally projecting pin rotatably supports a wheel or button 28 which tapers inwardly as at 29 to a hub 30 of reduced diameter. In use the shaft of the arrow 31 to be discharged is supported upon the rim of the wheel or the button and against the side of the post 19B. When released the lower inner feather 32 travels through the notch between the post and the reduced hub 30 of the button so that only the outer portion of the feather comes in contact with any part of the arrow rest. Further the wheel or button 28 is rotated by advancing motion of the shank of the arrow so that the feather 32 travels easily over the contacting portions of the arrow rest with a minimum of wear. With either form of the rest described, the location of the rest members 25 or 28 can be selectively adjusted to suit the desires of the Bowman.

What is claimed as new is:

1. In combination with an archery bow having a sight window with an upright side wall and flat floor, arrow supporting mechanism comprising a hollow box open at the top and an inner side supported upon the floor of said window opening and secured against the side wall of the window by screws passed through ears on the box,

a slide block transversely slidably mounted within said box and retained vertically therein,
an adjusting screw passed through the outer end of said box and threadedly engaged through said slide block,
an upright post swivelly mounted in said block and projecting upwardly thereabove,
a support arm projecting laterally from said post intermediate of the top of the post and said block,
and a spring engaged between said post and said block and biasing said arm to laterally outwardly and forwardly projecting position in the neutral position of said spring whereby the arm supports the shaft of an arrow to be released and rotates forwardly against spring tension upon the release of the arrow.

2. In combination with an archery bow having a sight window with an upright side wall and flat floor,
arrow supporting mechanism comprising a hollow box open at the top and an inner side supported upon the floor of said window opening and secured against the side wall of the window by screws passed through ears on the box,
a slide block transversely slidably mounted within said box and retained vertically therein,
an adjusting screw passed through the outer end of said box and threadedly engaged through said slide block,
a spring compressed between said block and said box to bias the block inwardly,
an upright post swivelly mounted in said block and projecting upwardly thereabove,
a support arm projecting laterally from said post intermediate of the top of the post and said block,
and a second spring engaged between said post and said block and biasing said arm to laterally outwardly and forwardly projecting position in the neutral position of said last spring whereby the arm supports the shaft of an arrow to be released and rotates forwardly against spring tension upon the release of the arrow.

3. In combination with an archery bow having a sight window with an upright side wall and flat floor,
arrow supporting mechanism comprising a hollow box supported upon the floor of said window opening and secured against the side wall of the window by screws passed through ears on the box,
a slide block transversely slidably mounted within said box and retained vertically therein,
an adjusting screw passed through the outer end of said box and threadedly engaged through said slide block,
an upright post mounted in said block and projecting upwardly thereabove,

a support arm projecting laterally from said post intermediate of the top of the post and said block,
and a spring biasing said arm to laterally outwardly and forwardly projecting position in the neutral position of said spring whereby the arm supports the shaft of an arrow to be released and rotates forwardly against spring tension upon the release of the arrow.

4. In combination with an archery bow having an upright side wall,

arrow supporting mechanism comprising a hollow box secured against the side wall by screws passed through ears on the box,

a slide block transversely slidably mounted within said box and retained vertically therein,
an adjusting screw passed through the outer end of said box and threadedly engaged through said slide block,

an upright post swivelly mounted in said block and projecting upwardly thereabove,

a support arm projecting laterally from said post intermediate of the top of the post and said block,
and a spring engaged between said post and said block and biasing said arm to laterally outwardly and forwardly projecting position in the neutral position of said spring whereby the arm supports the shaft of an arrow to be released and rotates forwardly against spring tension upon the release of the arrow.

5. In combination with an archery bow having an upright side wall,

arrow supporting mechanism comprising a hollow box secured against the side wall,
a slide block transversely slidably mounted within said box and retained vertically therein,

an adjusting screw passed through the outer end of said box and threadedly engaged through said slide block,

an upright post mounted in said block and projecting upwardly thereabove,

a support arm projecting laterally from said post intermediate of the top of the post and said block,
and a spring biasing said arm to laterally outwardly and forwardly projecting position in the neutral position of said spring whereby the arm supports the shaft of an arrow to be released and rotates forwardly against spring tension upon the release of the arrow.
